UNITED STATES PATENT OFFICE.

JAMES A. NOLAN, OF BOWERSTON, OHIO.

STOP FOR MINING-CARS.

1,072,977.

Specification of Letters Patent. Patented Sept. 9, 1913.

Application filed August 7, 1912. Serial No. 712,938.

To all whom it may concern:

Be it known that I, JAMES A. NOLAN, a citizen of the United States, residing at Bowerston, in the county of Harrison and 5 State of Ohio, have invented new and useful Improvements in Stops for Mining-Cars, of which the following is a specification.

In its specific adaptation the invention is primarily intended for arresting the movement of mining cars at a given point, such 0 as the platform or like device of an elevator and retaining the car upon such platform during its ascent or descent.

The invention may be utilized for stopping and holding carriers of different kinds, thereby preventing displacement of the carrier from the elevating platform or like device during its ascent or descent.

The invention provides a stop mechanism 0 which is adapted, to be automatically operated by means of the car to release the previous car and to automatically reset itself to engage and hold the next car.

The invention contemplates a mechanism 5 embodying a trip, a stop and an intermediate actuating means, the stop being mounted upon the platform or like elevating part and the trip being located at one side of the platform in position to be engaged by the 0 car, and the actuating means having a part mounted upon the platform and a part attached to the structure adjacent to and forming part of the elevator shaft.

The invention consists of the novel features, details of construction and combination of parts, which hereinafter will be more particularly set forth, illustrated in the accompanying drawings, and pointed out in the appended claim.

Referring to the drawings, forming a part 0 of the specification, Figure 1 is a detail view, showing the normal position of the parts. Fig. 2 is a detail view, showing the position 5 of the parts when automatically actuated by the approaching car to release the car from the platform. Fig. 3 is a top plan view. Fig. 4 is a modification.

Corresponding and like parts are referred 0 to in the following description, and indicated in all the views of the drawings, by the same reference characters.

The numeral 1 designates an elevator shaft and 2 the platform or like movable part by means of which the cars or other 5 carriers are elevated or lowered. A stop 3 is mounted upon the platform 2 in position

to engage a mining car 4 or other carrier to arrest its movement and hold it in proper position upon the platform. The stop 3 has a vertical movement and when lowered clears 60 the car which may pass from the platform and when elevated engages the advancing car and arrests its movement. A lever 5 is arranged beneath the platform 2 and is carried thereby. One end of the lever 5 is in engagement with the stop 3 or a part 65 pendent therefrom. The other end of the lever 5 is adapted to engage a cam 6 and is operated thereby to depress or lower the stop 3. The cam 6 is mounted upon a part of the 70 elevator shaft. A trip 7 is located at one side of the elevator shaft in position to be engaged by the advancing car. A rod or bar 8 connects the trip 7 with the cam 6.

When the platform 2 is at the lower end 75 of the elevator shaft to receive a loaded car and to discharge an empty car the end of the lever 5 engages the cam 6 and as a loaded car approaches the platform it operates the trip 7 to effect the release of an empty 80 car in the event of one being located on the platform, said empty car being pushed from the platform by the advancing loaded car. This result is accomplished by movement of the cam 6 which elevates the end of the 85 lever 5 resting thereon, thereby depressing the opposite end of the lever 5 and lowering the stop 3 so as to clear the empty car and admit of its being pushed from the platform. As soon as the loaded car clears the 90 trip 7 the parts assume a normal position,

with the stop 3 elevated so as to engage the loaded car and arrest its forward movement. A second stop 9 mounted upon the 95 platform 2 prevents a rebound of the loaded car and acts jointly with the stop 3 to hold the car in position upon the platform. The stop 9 prevents any return of the car in the event of the platform inclining in an opposite direction to the approach of the car. 100

When the loaded car is upon the platform 2 the latter may be elevated to carry the loaded car to the upper landing for a discharge of the load, after which the platform is lowered, the empty car being released and moved from the platform in the manner hereinbefore stated by the action of the next loaded car, the operation being entirely automatic.

In the modification shown in Fig. 4 the 110 stop 13 is connected to the lever 12 intermediate of its ends and normally occupies

a lowered position to admit of an empty car being pushed from the platform by a loaded car. As the empty car passes from the platform it engages the lever 11 and moves it to lift the cam 10 and the weighted end of the lever 12, thereby elevating the stop 13 to a position to engage the advancing loaded car and arrest its movement. This is of advantage when the tipple is located at some distance from the shaft. In this form the weighted end of the lever 12 holds the stop 13 lowered, whereas in the form shown in the other views the weighted end of the lever 12 when unsupported holds the stop 13 elevated.

From the foregoing description, taken in connection with the accompanying drawings, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely

illustrative, and that such changes may be made when desired as are within the scope of the claim appended hereto.

Having thus described the invention what is claimed as new, is:—

In combination a vertically movable platform, a stop mounted upon the platform and adapted to arrest the movement of a carrier, a trip mounted upon the approach to the platform and located in the path of the carrier, a cam mounted independently of the platform, connecting means between the cam and trip, and a lever mounted upon the platform and movable therewith and having one end arranged to operate the said stop and having its opposite end adapted to be engaged by the said cam whereby movement of the trip effects a depression of the stop.

In testimony whereof I affix my signature in presence of two witnesses.

JAMES A. NOLAN.
